UNITED STATES PATENT OFFICE.

LOWELL W. SHIELDS, OF ROCHESTER, NEW YORK, ASSIGNOR TO HICKOK MANUFACTURING COMPANY, INC., OF ROCHESTER, NEW YORK, A CORPORATION OF NEW YORK.

CREASING MACHINE.

Application filed October 19, 1923. Serial No. 669,596.

To all whom it may concern:

Be it known that I, LOWELL W. SHIELDS, a citizen of the United States, and resident of Rochester, in the county of Monroe and State of New York, have invented certain new and useful Improvements in Creasing Machines, of which the following is a specification.

The present invention relates to creasing machines and an object of the invention is to provide a creasing machine designed for creasing loops, such as used in belts, straps, harness or the like. Another object of this invention is to provide a machine in which the creasing operations are so simplified that the expense of creasing loops is reduced to a minimum. A further object of the invention is to provide a simple and inexpensive means of feeding loops to and from a creasing mechanism. Still another object of the invention is to provide a creasing mechanism which will form simultaneously creases in the four corners of a loop.

To these and other ends, the invention consists of certain parts and combinations of parts, all of which will be hereinafter described: the novel features being pointed out in the appended claims.

In the drawings:

Fig. 1 is a side view of a creasing machine constructed in accordance with this invention, parts of the standard of the machine being broken away;

Fig. 2 is a front view of the machine;

Fig. 3 is a view showing the top cover plate of the creasing mechanism removed and the shaping die in horizontal section;

Fig. 4 is a section on the line 4—4, Fig. 3;

Fig. 5 is a section on the line 5—5, Fig. 3; and

Fig. 6 is a perspective view of the shaping die and feeding or guide bar leading thereto.

In the illustrated embodiment of the invention, there is provided a hollow standard 1 having a plate 2 bolted to the upper end thereof at 3. This plate has a casting 4 bolted thereto at 5, the top of such casting having a central opening 6, and having arranged beneath it a discharge conduit or chute 7 for the creased loops 8, this chute extending downwardly in the standard and laterally at 9 through one side of the standard as illustrated in Fig. 1. The top of the

casting 4 serves as a bed plate for the creasing mechanism and has extending upwardly therefrom and integrally therewith segmental pieces 10 spaced apart so as to provide guideways between them, the guideways thus formed being radial to the opening 6. 65 On these guideways pressure or creasing devices 11 and 12 operate, the creasing devices 11 being two in number and being duplicates of each other and the creasing devices 12 also being two in number and being duplicates 65 of each other, but being, in this instance, different in form from the creasing devices 11. Each of the creasing devices is mounted on a rod 13 which has a head 14, limiting the movement of the creasing devices on the rod in one direction. The rod is rigidly secured to a block 15 and is surrounded by a helical spring 17 arranged between the block and the creasing head, so that the creasing head or device is resiliently connected with the block. Both the block and the head are guided at their sides by engagement with the sides of the quadrantal projections 10. Each block 15 preferably also carries an anti-friction roller 18 for engagement by a cam surface 19 on the inner periphery of an operating ring 20, the operating ring having, in this instance, worm wheel teeth 21 for engagement with the worm 22. The worm 22 is driven in any suitable manner as by a 80 sprocket 23 on the worm shaft connected by a sprocket chain 24 with the shaft of a motor 25.

It is apparent that the turning of the operating ring 20 through the worm 22 causes the 90 cams 19 to cooperate with the rollers 18 on the blocks 15 and move said blocks with the pressure or creasing devices radially inward to cooperate with one of the loops 18 supported on a shaping die to be hereinafter 95 more particularly described. A spring 26 anchored at 27 to the pins on the bed 4 and at 28 to pins on opposite sides of the creasing or pressure devices 11 and 12 tend to move said devices with the heads 15 outwardly. The springs 17 permit said pressure or creasing devices to adapt themselves to loops of different thicknesses.

The shaping die hereinbefore mentioned is in the form of a head 29 formed with two wide sides and two narrow sides, both the narrow sides and the wide sides being concaved at 30 so that sharp corners 31 are pro-

vided on the die. The pressure or creasing devices are also curved so that the sides and ends of a loop are pressed inwardly on the shaping die, thus creating sharp corners in the loop and providing a loop which is substantially permanent in its formation.

The die is preferably suspended from a point above the creasing mechanism, so that the loops may be passed or forced downwardly from the shaping die into the chute

7. In this instance, the die is suspended by a guide bar 32 which has its upper end formed with a bayonet slot 33 engaged over a headed pin 34 formed on the end of a bracket 35 projecting upwardly from a top plate 36 which covers the creasing mechanism and has a central opening 37 through which the shaping die may extend.

In the operation of the invention the loops are fitted upon a guide bar or strap 32 with a shaping die 29 at one end thereof and are then suspended from the headed projection at the end of the bracket 35 so that the shaping die lies within the field of operation of the creasing mechanism. Thereafter the creasing mechanism is started in operation and the pressure or creasing devices move toward one of the loops on the die, pressing the sides and ends of the loop inwardly, so as to form sharp corners at the corners of the shaping die. After a loop has been creased another loop is moved to creasing position, displacing the creased loop which moves downwardly on the shaping die and displaces one of the creased loops below it into the chute 7. This is continued until all of the loops on the guide bar have been creased when another guide bar and shaping die is introduced into the machine.

40 From the foregoing it will be seen that there has been provided a creasing machine especially adapted for creasing loops in connection with belts, straps, harness, or the like. Loops are creased on a shaping die which is suspended in such a manner that after the creasing operation they may be discharged readily downward from the die. The suspending means is in the form of a bar or guide on which the shaping die is mounted, this guide or bar directing the loop therefrom onto the shaping die. Creasing or pressure devices are preferably yieldingly mounted and cooperate with the sides and ends of the loops to force them into concave faces on the die and form sharp corners in the loops. In this instance, the creasing devices are moved radially and operated through a cam ring which has worm wheel teeth engaged by a suitably driven worm.

60 What I claim as my invention and desire to secure by Letters Patent is:

1. A loop creasing machine comprising a guide about which the loop extends and a shaping die rigidly connected to the guide so that the loops to be shaped can move from

the guide to and about the die, and movable creasing devices operating upon the loops on the shaping die.

2. A loop creasing machine comprising a suspended guide bar about which the loops extend, a shaping die rigidly arranged at the lower end of the guide bar and onto and about which the loops are fed from the guide bar, and creasing means operating upon the loops on the shaping die.

3. In a loop creasing machine, a guide bar about which the loops extend having a shaping die at one end thereof to receive about it the loops from the guide bar.

4. In a loop creasing machine, a guide bar about which the loops extend having a shaping die at one end thereof to receive the loops from the guide bar combined with means for detachably suspending said guide bar from its upper end, and creasing means operating upon the loops on the shaping die.

5. A creasing machine comprising a suspended guide bar, a shaping die arranged at the lower end of the guide bar to receive articles from the latter, means operating upon the articles on the shaping die to crease the articles, and a chute arranged below said shaping die to receive such articles from the die.

6. A creasing machine comprising a suspended shaping die, and creasing devices arranged about said die to operate upon an article thereon, said creasing devices being yieldingly mounted.

7. A creasing machine comprising a suspended shaping die, and creasing devices arranged about said die to operate upon an article thereon and radially movable.

8. A creasing machine comprising a suspended shaping die, a plurality of creasing devices arranged about the die and movable to operate upon the articles to be shaped on the die, and a cam ring for operating said creasing devices.

9. A creasing machine comprising a shaping die, a bed having an opening over which said shaping die is suspended, creasing devices radially movable on the bed to cooperate with said shaping die, roller carrying blocks yieldingly connected with the creasing devices, and a cam ring mounted on the bed about the blocks and the creasing devices and cooperating with the rollers on the blocks to force the creasing devices into cooperative relation with the shaping die.

10. A creasing machine comprising a bed having an opening through which the creased articles are discharged, a shaping die suspended above said opening, radially movable creasing devices guided on the bed, and a rotary cam ring surrounding said creasing devices and arranged to force the creasing devices inwardly into cooperation with the shaping die.

11. A creasing machine comprising a bed

having an opening and guides extending radially with reference to said opening, creasing devices movable on the guides, blocks movable on the guides and resiliently connected with the creasing devices, a spring moving the creasing devices and blocks outwardly, a cam ring surrounding said blocks and arranged to move the latter with the creasing devices inwardly, and a shaping die 10 with which said creasing devices are adapted to cooperate when moved inwardly.

12. A loop creasing machine comprising a shaping die having concave sides, concave ends and sharp corners between the ends and sides, the shaping die being constructed to 15 permit a loop to surround the same, and creasing devices arranged to cooperate with the sides and ends of the shaping die to force the loop into engagement with the concave faces to crease the loops at the sharp edges.

LOWELL W. SHIELDS.
